FOREIGN PATENT DOCUMENTS

WO 2011/146166 A1 11/2011

Primary Examiner — Richard E Chilcot*(74) Attorney, Agent, or Firm* — The Webb Law Firm(57) **CLAIM**

The ornamental design for a microinfuser, as shown and described.

DESCRIPTION

FIG. 1 is a perspective view of a microinfuser in accordance with an embodiment of the present invention.

FIG. 2 is a bottom view of the microinfuser of FIG. 1 in accordance with an embodiment of the present invention.

FIG. 3 is a rear view of the microinfuser of FIG. 1 in accordance with an embodiment of the present invention.

FIG. 4 is a top view of the microinfuser of FIG. 1 in accordance with an embodiment of the present invention.

FIG. 5 is a front view of the microinfuser of FIG. 1 in accordance with an embodiment of the present invention.

FIG. 6 is a right side view of the microinfuser of FIG. 1 in accordance with an embodiment of the present invention; and,

FIG. 7 is a left side view of the microinfuser of FIG. 1 in accordance with an embodiment of the present invention.
